UNITED STATES PATENT OFFICE.

CHARLES SMITH, OF BURNLEY, COUNTY OF LANCASTER, ENGLAND,
ASSIGNOR TO WILLIAM WHITTAKER, OF SAME PLACE.

APPARATUS FOR SUPPLYING FUEL TO STEAM-BOILERS.

SPECIFICATION forming part of Letters Patent No. 224,237, dated February 3, 1880.

Application filed July 8, 1879. Patented in England, August 21, 1877.

To all whom it may concern:

Be it known that I, CHARLES SMITH, of Burnley, in the county of Lancaster, in that part of the United Kingdom called "England," 5 mechanic, have invented new and useful Improvements in Apparatus for Supplying Fuel to Steam-Boilers and other Furnaces, which improvements are fully set forth in the following specification, reference being had to the accompanying drawings.

To afford a uniform intermittent supply of fuel to the stoker or to the furnace from the feed-hopper, and direct the fuel thrown by the fans or other medium upon and over the fire, 15 according to this my invention, I employ a hopper or hoppers the bottom or lower part of which is in communication with a cylinder the upper and lower sides of which are provided with openings for the reception and exit of fuel. Within 20 in the cylinder is a roller, caused to rotate slowly by gear wheels or other driving apparatus. The periphery of the roller is, at intervals, recessed, forming receptacles, within which coal, as the receptacle comes under the 25 hopper, is received. The continued rotation brings the receptacle over the exit-opening through the cylinder, by way of which the fuel passes out to the furnace or to the mechanical stoker, and so as each recess passes 30 under the hopper it becomes filled with fuel, to be discharged on reaching the exit-opening. When two-flued boiler or double furnace is to be supplied there may be one of such apparatus to each furnace or stoker, or one apparatus 35 may supply both furnaces or stokers. In the latter case there will be a double incline placed immediately under the exit-opening, so that part of the fuel may pass down the incline to the right hand and part down the incline to the left hand; or the receptacles may 40 extend a portion of the length of the roller, and the receptacles on the right hand supply the furnace or stoker on the right, the receptacles to the left supplying the left of the furnace or stoker.

The receptacles may be of various forms, so as to vary the discharge from any one receptacle.

It will be obvious that the roller, instead of

being entirely inclosed within a cylinder, would 50 answer the same purpose if partly inclosed or embraced by a concave neck or concave bottom of the hopper.

In connection with the improved feed-roller above described, I employ for double-flued 55 boilers, two fuel-fans or rotary distributers, partly inclosed in boxes and speeded by means of pulleys.

The plate or plates for diverting and directing the fuel thrown by the fan or fans are placed 60 within the flue and supported by a shaft or other axis or hinges, and such plate or plates may have a gradual rising-and-falling motion imparted by tappet or its equivalent; or the plate or plates may be stationary, the angle 65 of inclination being readily adjusted by screw-shaft, according to the speed and throw of the fans, so that the fuel shall be diverted and directed upon and over the whole surface of the bars, the throwing of fuel upon and over the 70 bridge being entirely obviated.

Such being the nature and object of this my said invention, I will proceed to describe the same in detail; and in order that the invention may be fully understood, I have hereunto annexed two sheets of drawings illustrative thereof, and have marked the same with figures and letters of reference, the same letter referring to the same part in the several views or figures.

Figure 1 is a front elevation of double-flued 80 boiler having my apparatus attached. Fig. 2 is a side elevation of Fig. 1, partly in section. Figs. 3, 4, 5, 6, 7, 8, 9, 10, and 11 are details drawn to an enlarged scale.

A is a hopper or hoppers, the bottom or lower 85 part of which is in communication with a cylinder, B, the under side of which is provided with an opening, F, for the exit of fuel. Within the cylinder is a roller, C, caused to rotate slowly by gear-wheels D, D', D², and D³, or other driving apparatus. The periphery of the roller is (at intervals apart) recessed, forming receptacles E, within which coal (as the receptacle comes under the hopper A) is received. The continued rotation brings the receptacles E over exit-opening F through the cylinder B, by way of which the fuel passes 90 out to the furnace or to the mechanical stoker, 95

and so as each recess E passes under the hopper A it becomes filled with fuel, to be discharged on reaching the exit-opening F.

When a two-flued boiler or double furnace is to be supplied there may be one of such apparatus to supply both furnaces or stokers, as shown at Figs. 1 and 2. In the latter case there will be a double incline, G, placed immediately under the exit-opening F, so that part of the fuel may pass down the incline to the right hand and part down the incline to the left hand; or the receptacles may extend a portion of the length of the roller. (See Figs. 6 and 7.) The receptacles on the right hand supply the furnace or stoker on the right, the receptacles to the left supplying the left of the furnace or stoker.

The receptacles may be of various forms, so as to vary the discharge from any one receptacle. (See Figs. 8 and 9.)

It will be obvious that the roller, instead of being entirely inclosed within a cylinder, as at Figs. 3 and 4, would answer the same purpose if partly inclosed or embraced by a concave neck, as at Fig. 5, or concave bottom of the hopper.

In connection with the improved feed-roller above described, I employ for double-flued boilers two fuel-fans or rotary distributors, H, partly inclosed in boxes, and speeded by means of pulleys L.

The plate or plates J, for diverting and directing the fuel thrown by the fan or fans H, are placed within the flue and supported by a

shaft or other axis or hinges, K, and such plate or plates may have a gradual rising-and-falling motion imparted by tappet or its equivalent; or the plate or plates may be stationary, the angle of inclination being readily adjusted by screw-shaft M, according to the speed and throw of the fans, so that the fuel shall be diverted and directed upon and over the whole surface of the bars, the throwing of fuel upon and over the bridge being entirely obviated.

Having thus fully described the nature and particulars of this my said invention, together with the manner in which the same is to be performed or carried into practical effect, I would observe that in order to fully explain the application and use of my invention it has been absolutely necessary to refer to and describe parts which are not new. I would therefore have it understood that I limit and confine my claims to—

The combination, with a suitable hopper and a roller arranged above discharge-mouth of the same, and having peripheral recesses, of one or more fans or distributors and mechanism for imparting motion thereto, and one or more pivoted deflecting-plates made adjustable for diverting or directing the fuel projected by the said fans or distributors over the surface of the bars, substantially as herein shown and described.

CHARLES SMITH.
